[57] CLAIM

The ornamental design for a reconfigurable toy vehicle, substantially as shown and described.

DESCRIPTION

FIG. 1 is a top perspective view of a reconfigurable toy vehicle showing my new design;
FIG. 2 is a top plan view;
FIG. 3 is a left elevational side view which is a mirror image of the right elevational side view;
FIG. 4 is a front elevational view;
FIG. 5 is a rear elevational view;
FIG. 6 is a bottom plan view;
FIG. 7 is a front elevational view of the design shown in FIGS. 1 through 6 reconfigured in the form of a toy robot;
FIG. 8 is a right elevational side view which is a mirror image of the left elevational side view;
FIG. 9 is a rear elevational view;
FIG. 10 is a top plan view; and
FIG. 11 is a bottom plan view.
